UNITED STATES PATENT OFFICE

BEATRICE M. STODDARD, OF DEDHAM, MASSACHUSETTS, ASSIGNOR TO DOROTHY DEWEY COMSTOCK, OF DEDHAM, MASSACHUSETTS, DOING BUSINESS AS THE KIDDIE-RHESTER CO.

PLAY PEN

Application filed June 8, 1929. Serial No. 369,300.

This invention relates to portable cribs or play pens of the foldable and extensible type disclosed in the patent to Dorothy D. Comstock No. 1,463,459 dated July 31, 1923. The principal object of the invention is to provide, in association with a baby pen of this class, a sheet or cover member constructed and arranged to serve as a bottom pad for the extended pen during use as well as a casing adapted to enclose the folded pen for transportation. Further objects reside in the structural features of the devices hereinafter described and illustrated in the accompanying drawings, in which:

15 Fig. 1 is a top view showing the sheet member attached to the bottom of the erected baby pen and illustrating, in broken lines, the folded pen in position to be enclosed within the sheet casing;

20 Fig. 2 is a top view of the collapsed pen; Fig. 3 is a perspective view of the folded pen partially enclosed within the casing; and

Fig. 4 is a similar view showing the casing fastened around the collapsed pen.

25 As more fully described in said Comstock patent, the baby pen or crib may comprise six pivotally connected sections 11, 12, 13, 14, 15 and 16, each including longitudinal top and bottom rails 17 connected by transverse 30 rods or spindles 18; but any desired even number of sections of approximately the same length may be employed, and the individual sections may be formed of any suitable materials as desired. When extended to form an erected pen, these sections are so placed and interconnected as to form a rectangular enclosure preferably twice as long as it is wide, the long sides comprising two sections joined end to end.

40 The sections are suitably hinged at three of the corners and midway of the sides, as by hinges 19 applied at the abutting ends of the rails 17, while the separable corner of the erected frame is provided with detachable locking fastenings, as indicated at 20 in Fig. 1. Separable fastenings 21 similar to the fastenings 20 may be provided at the abutting ends of the side sections, to lock said sections against relative angular movement.

45 The hinges 19 are so arranged that the frame

may be folded in zig-zag fashion by separating the fastenings 20 and 21 and swinging adjacent sections against each other. Thus, the folded or collapsed pen (Fig. 2) comprises a compact bundle in which the hinged sections 55 are disposed in parallel juxtaposition.

The sheet or cover member 27 which functions as a combined bottom mat and casing for the baby pen may be made of any suitable flexible material preferably water-proofed upon its outer surface by a layer or coating of water-repellent material; and its main body portion is preferably rectangular in shape and of such dimensions as to underlie the erected pen (Fig. 1) and to envelop the 60 folded frame (Fig. 3). The side margins of said body portions extend beyond the bottom rails so that they may be folded upon the outer sides of said rails and be detachably fastened thereto as by the cooperating stud 65 and socket members of suitable snap fasteners 28, the stud members of which are preferably affixed to the rails with the socket elements attached at the sheet margins. Thus, the sheet 27 may readily be attached beneath 70 the lower rails of the erected frame to serve as a bottom pad for the pen. The side fasteners are usually adequate to prevent displacement of the pad, but additional fasteners may obviously be provided at the ends 75 of the frame if desired.

In order that the sheet may also function as an enclosing casing for the folded pen, opposed extensions or side wings 29 are preferably provided to fold over the opposite 85 ends of the collapsed frame. These wings extend transversely of the pen when the sheet is utilized as a bottom mat, and are provided at their respective margins with stud members 30 which cooperate with the socket 90 elements of the fasteners 28 to provide the casing fastenings 31 of Fig. 4, when the sheet is folded over the collapsed pen to envelop the juxtaposed sections.

95 Aligned stud members 32 are provided near one end of the sheet to cooperate with complementary socket elements 33 arranged along the opposite margin thereof in furnishing the separable fasteners 34 for uniting the overlapped ends of the casing (Fig. 100

4). One of the center sections of the collapsed crib frame, for example end section 14, may be provided with an upstanding handle 35, and the casing may have a complementary, marginally reinforced slot or aperture 36 through which the handle extends to afford ease in transporting the encased pen.

In order conveniently to enclose the pen within the casing, the folded frame may be laid flatwise upon the extended sheet, substantially in the position shown in broken lines in Fig. 1. The side wings or flaps 29 are then folded over the ends of the juxtaposed sections, the longer end of the sheet is turned over and upon the upper side of the structure and attached to the wing portions by some of the cooperating fasteners 31 (Fig. 3); and the shorter end of the sheet is folded upwardly and over the opposed sheet edge, and then attached to the wings by other fastenings 31 and to said opposite sheet edge of the fasteners 34 (Fig. 4). The pen is accordingly entirely enclosed within in the casing, and the encased pen furnishes a compact package which may readily be carried from place to place or transported over considerable distances without inconvenience. The spaces between the spindles of the folded sections afford storage room within in the casing for infant's clothing, bedding, toys or other accessories.

The extended crib or pen with its attached bottom mat may be placed outdoors, either on the ground or upon a porch or platform, or may be erected indoors upon a bed or on the floor. The fastened sheet provides a smooth bottom pad which protects the infant from dirt, dampness or insects when out of doors, and also guards against damage to the floor or bed coverings when the pen or crib is used in the house. An infant playing within the pen can not move the frame off the mat or push the pen along the floor, and is less likely to tilt the sides of the frame while standing upon its attached bottom. The sheet member is simple and economical to manufacture and because of its double purpose is useful at all times; and the provision of common fastening elements for securing the pad to the pen frame and attaching the overlapped margins of the casing obviates the necessity of duplicating fasteners and consequently encumbering the sheet or the pen with separate fastening elements for the respective uses.

From the foregoing, it will be evident that characteristic features of the invention consist in that the cover has transverse and longitudinal dimensions at least substantially equal to corresponding dimensions of the erected pen, as shown in Fig. 1; in that the length of the cover is at least approximately equal to a circumferential dimension of the collapsed pen so that it may be wrapped

theretround as shown in Fig. 3; in that the cover has lateral portions to fold over the ends of the collapsed pen, these portions preferably being in the form of extensions or flaps integrally connected with the sides of the cover; in that the transverse dimension of the cover is approximately equal to the length of each of the collapsed sections; in that the longitudinal dimension of the cover is approximately equal to the length of the erected pen and twice the length of each section and to the aforesaid circumference of the collapsed sections; and in that said extensions correspond in length to the thickness of the collapsed sections and in width to the height of each section.

I claim:

1. In combination with a portable pen comprising a plurality of thin, rectangular sections pivotally interconnected to form an upright, rectangular enclosure when erected and to fold into parallel juxtaposition when closed, a combined bottom mat and casing consisting of a sheet of flexible material having a substantially rectangular body portion shaped to underlie the bottom of the erected pen and to fold over the bottom, sides and top of the folded pen, and having a pair of oppositely disposed, substantially rectangular side wings, the wings being substantially as long and as wide as the respective ends of the closed pen to cover said ends when the sheet is used as a casing, the opposed margins of the body portion and wings of the casing overlapping each other completely to enclose the folded pen therewithin, cooperating fastener elements spaced along said margins for securing the casing about the folded pen, and fastener elements spaced along the bottom of the sections at the sides of the erected pen, cooperating with the fastener elements at the side margins of said body portion for attaching the sheet to the bottom of the erected pen.

2. A combined bottom mat and casing for use with a portable pen having a plurality of rectangular sections pivotally interconnected to form an upright enclosure when erected and to fold into parallel juxtaposition when closed, comprising a sheet of flexible material having a substantially rectangular body portion shaped approximately to underlie the bottom of the erected pen and to fold over the bottom, sides and top of the folded pen, and having a pair of oppositely disposed substantially rectangular side wings, the wings projecting beyond the sides of the erected pen when the sheet is used as a mat and being longer and wider than the respective ends of the closed pen, so that the wings cover said ends and overlap the top, bottom and one side of the erected pen when the sheet is used as a casing, fasteners at the side margins of the body portion for attaching the sheet to the bottom of the erected pen,

cooperating fastener members at the opposite ends of the body portion for separably connecting said ends when the sheet is used as a casing, and fastener elements at the margins of the wings cooperating with the fasteners at the side margins of the body portion for detachably securing said margins together when the sheet is enveloped about the folded pen, thereby completely to enclose the folded pen.

19 Signed by me at Boston, Mass. this 16th day of May, 1929.

BEATRICE M. STODDARD.
